 Bridgeport, Conn., a corporation of Delaware

Application July 3, 1947, Serial No. 758,832

12 Claims. (Cl. 102—42)

1

This invention relates to ammunition, and more particularly to filler wads for shot shells.

The function of the filler wad or wad column, which in a shot shell separates the propellant powder from the shot mass, is twofold. First, the wadding functions as a gas seal, being propelled forward by the gas pressure behind it and transmitting this pressure to the shot charge, preferably without any leakage of gas through or around the wadding and into the shot charge; second, the wadding should cushion the impact of the suddenly generated powder gas against the shot in such a way that the shot is pushed and gradually accelerated, instead of being struck a sudden hammer blow. In a 12 gauge shot shell, the shot charge has a weight of 1 to 1½ oz.; hence, a substantial inertia. Moreover, the sudden generation of a large quantity of gas in the confined space behind the wadding is productive of undesirably high pressures unless the wadding is susceptible to substantial compression, thereby enabling a certain expansion of the gas before and during the initial movement of the shot charge.

The two functions of the wadding are to a certain extent contradictory. A rigid tightly barrel sealing body is required to prevent gas leakage, while at the same time a highly compressible body is desirable to prevent excessive peak pressures and enable a more gradual acceleration of the shot. Certain attempts have heretofore been made to provide a wad column of two or more different elements of different properties, one having a gas sealing function and another being of compressible character. However, prior attempts to provide a highly compressible wad have not been satisfactory, by reason of the difficulty in providing a sufficiently compressible medium which will not be disintegrated under firing stresses. The maximum pressure generated in the firing of an ordinary shot shell is of the order of 10,000 pounds per square inch, and this pressure is transmitted from the powder chamber through the wadding to the inert shot charge. Such compressible materials as have been used hitherto disintegrate under these high pressures into fragments which at gun muzzle are dispersed into a cloud which obscures the shooter's view and may be blown back in his face.

The present invention comprises the discovery of a class of materials which can be easily and cheaply formed into one-piece wads which are very highly compressible and on compression are packed into a thin disk that is projected from the shotgun barrel with little or no fragmentation.

2

These materials are of a group which for the purpose of this specification will be called "cellular plastics." They are also known by such terms as "foam plastics" or "expanded plastics."

5 In the drawings:

Fig. 1 is a side view of a shot shell, a portion of the body wall being broken away to illustrate a wad according to the invention.

10 Fig. 2 is an enlarged fragmentary side view of an unfired wad.

Fig. 3 is a fragmentary, sectional elevation of a fired wad, enlarged in the same proportions as Fig. 2 so that Figs. 2 and 3 show the comparative lengths of the unfired and fired wad.

15 Fig. 4 is an enlarged fragmentary cross-section of a wad embodying the invention, being substantially a copy of a photo-micrograph.

For the purpose of this specification, the term "plastic" or its plural form of "plastics" are used 20 as nouns identifying generally that class of synthetic organic polymers which are susceptible to formation and/or shaping in a fluid or semi-fluid condition and upon proper processing yield bodies which at ordinary temperatures are continuous and rigid at least to the extent of being self-sustaining. A variety of addition agents for enhancing particular properties may be included. Such plastics include phenolics, aminoplasts, 25 vinyls, acrylics, polyamids, polystyrene, polyethylene, polyesters, and cellulose esters and ethers.

The plastics in their ordinary form are continuous and substantially homogeneous bodies. It has recently been found that plastics generally are susceptible to formation into a cellular structure of greatly reduced apparent density as compared with their density in their normal condition. The specific gravity of the solid plastics varies from about .9 to about 1.33, these figures corresponding to a density range of 30 from about 56 pounds per cubic foot to about 82 pounds per cubic foot. When produced in cellular form, the apparent density may be as low as 1.5 pounds per cubic foot or even less. Such cellular plastics having an apparent density as high as 11 pounds per cubic foot have been made into 35 satisfactory shot shell wads.

Taking cellulose acetate as an example, its density in its common commercial form ranges from about 79 pounds per cubic foot to somewhat over 82 pounds per cubic foot. By proper treatment, it can be expanded into substantially rigid and coherent bodies having densities from 1.5 pounds per cubic foot to about 8 pounds per cubic foot. One method of accomplishing this may be 40 outlined as follows:

50

55

A pulverulent or granular material comprising 97% or 98% unplasticized cellulose acetate, the remainder being chiefly water, is admixed with 9% to 20% of a volatile liquid which is non-solvent for the cellulose derivative at 70° F. and a solvent therefor above about 160° F., say an admixture of ethyl alcohol and acetone. This composite is extruded from an extrusion machine at a temperature between 350° F. and 400° F. with a back pressure of at least 300 pounds per square inch. Under these conditions of temperature and pressure the mass has the consistency of a stiff paste or dough. As the mass is extruded through a small orifice, there is a sudden decrease in pressure which permits the superheated solvent to flash vaporize and form the expanded body. The exposure of the expanded body to the atmosphere after expansion permits cooling and evaporation of the remaining solvent to rigidify the material. The expanded body consists of a great multiplicity of uncommunicating cells separated by a honeycomb web or lattice of the solid material. A more uniform texture can be secured by the addition to the mixture of a suitable quantity of a solid pulverulent material which is insoluble in the solvent and is inert to the plastic, such as barium sulfate, powdered copper, powdered aluminum, aluminum oxide, mica, fuller's earth, zinc oxide, etc. The solid grains act as nuclei for the formation of the gas bubbles which establish the individual and uncommunicating cells. Bodies of a desired cross-sectional configuration can be secured by associating a short guide of the desired cross-section with the extruding orifice. For example, a rod of a diameter of $\frac{3}{4}$ " may be secured by placing adjacent an orifice of a diameter of the order of 0.09" to 0.145", a tube of an interior diameter of $\frac{3}{4}$ " and about 3" or 4" long. The material expands and rigidifies with such rapidity that a longer guide tube is unnecessary. The porosity or density of the product is a function of the amount of solvent used in the mixture. The greater the amount of solvent the lower the density of the product. The lower density limit for a product suitable for the purposes of this application appears to be about 1.5 pounds per cubic foot, corresponding to a solvent content in the mixture of about 20%. Lower density materials are subject to undesirable fragmentation under shot shell firing pressures. The rigidity and coherency of the low density product may be augmented by adding to the starting material an appropriate amount, say 1 to 10% of a suitably dispersed fibrous material which is insoluble in the solvents and will withstand the rigorous temperature conditions, such for example, as glass fiber.

Other methods of preparing cellular plastics comprise the admixture with the pulverulent plastic of volatile or decomposable solids, or of soluble salts subsequently leached out by the use of a solvent, or the generation of steam by the heat of reaction of the constituents of a plastic such as urea formaldehyde in admixture with a catalyst.

A product comprising separate non-communicating cells is preferable for the purpose of the present invention. A structure of communicating cells, such as that produced by the use of 70 soluble salts, is less coherent and more easily disintegrated. A typical individual cell plastic, such as cellular cellulose acetate, will be crushed or permanently compressed under firing pressures to about 13% of its original length with 75

little if any fragmentation. After firing, the compressed wads, each bearing a dimpled shot pattern and having an average length of about .06", can be recovered substantially intact.

5 The cellular plastic wad is preferably used in conjunction with a gas sealing wad which is of conventional design, for example a felted fibrous construction as disclosed in the patent to Burghardt, No. 1,834,377, December 1, 1931, except 10 that, since it need not be compressible, it may be so compacted and impregnated with a high melting sealing and lubricating material as to form a superior and substantially perfect gas seal.

To obviate bore friction and abrasion, the cellular plastic wad is preferably surface lubricated, and the non-communicating cellular structure is effective to prevent unwanted penetration of the wad body by the lubricant, confining the lubricant to the surface, where it is useful.

15 Referring to the drawings, numeral 10 is a head of a shot shell comprising a body 11 which contains a charge of shot 12, a charge of powder 13, a gas sealing wad 14, and a compressible cellular wad 15 of the present invention. The cellular structure of the wad is clearly illustrated in Fig. 4, which is substantially a copy of a photo-micrograph. The comparative lengths of the wad 15 as loaded and the same wad 15' after firing are 20 shown in Figs. 2 and 3 which are on the same scale, each being enlarged approximately three times the dimensions used for a 12 gauge shot shell. In firing, the length and volume of the wad are reduced to not over about 13% of the original length and volume. For a 12 gauge shot shell, the original wad length is substantially $\frac{1}{2}$ ", the pattern of the adjacent shot is impressed in 25 its forward face on firing, and its length is reduced to a maximum of about .09" at the crests adjoining the shot cavities to a minimum of .04" at the bottom of the shot cavities. The average length is about .06", which means 30 that a powder expansion space having a length of about .44" and a volume of 87% of the original wad volume has been provided.

35 45 By the use of a highly compressible cellular plastic wad, it becomes possible to materially improve and perfect the gas sealing wad. Gas leakage into and past the wad column facilitates wad break-up and is ballistically detrimental. Prior 50 to the present invention, improvement in gas sealing has been handicapped by the necessity for making the gas sealing wad somewhat compressible. No material hitherto proposed as a cushion wad has been susceptible to an amount of compression which would enable the use of a substantially non-compressible gas-sealing wad without 55 producing excessive pressures. With the wad of this invention, complete gas sealing and standard velocity can be secured with pressures materially lower than accepted standards. Shot shells containing a cellular cellulose acetate wad and a gas sealing wad have been shot in comparison with a commercial imperfectly sealing wad column and with experimental shells containing a commercial wad and a gas sealing wad, with the following 60 65 results:

Cellular Plastic with Gas Seal		Commercial with Gas Seal		Commercial	
V	P	V	P	V	P
884	9,400	885	11,000	886	10,100
871	9,600	869	11,000	856	9,700
874	9,400	882	10,600	881	10,400

Each of the above figures is an average for 25 shots, and velocities the usual average over a range of 25 yards. All components of each compared group of shells except the wad column were identical. It will be seen that as compared with conventional and commercially acceptable wadding, the wadding of this invention gives pressures which are not only lower but more uniform, with no material difference in velocity, also that the tendency of a tight gas seal to cause excessive pressure has been completely overcome.

What is claimed is:

1. A shot shell wad comprising a unitary, substantially circular cylindrical body having substantially the diameter of the inside of a shot shell, said body consisting of a single piece, substantially the full size of said body, of a cellular, expanded, plastic containing a multiplicity of non-communicating empty cells separated by permanently crushable, relatively thin, walls of the solid plastic.

2. A shot shell wad according to claim 1, having a lubricated surface, the lubricant being confined to the surface portion by the non-communicating cell structure.

3. A shot shell wad according to claim 1, in which the cell defining material is an admixture of a plastic with 1% to 10% of a hardening and strengthening agent.

4. A shot shell wad according to claim 3, in which the hardening agent is fiber glass.

5. A shot shell wad according to claim 1, said single piece of cellular expanded plastic having, before crushing, an apparent density of not over 11 pounds per cubic foot.

6. A shot shell wad according to claim 1, in which the cellular expanded plastic is cellular cellulose acetate.

7. A shot shell wad according to claim 1, in which the cellular expanded plastic is cellular 40 styrene.

8. A shot shell wad according to claim 1, in which the cellular expanded plastic is cellular phenol formaldehyde.

9. A shot shell containing a charge of a propellant powder and a shot charge separated from said powder charge by a wad column comprising at least one cushion wad formed of a single piece of a cellular expanded plastic containing a multiplicity of non-communicating empty cells separated by permanently crushable, relatively thin walls of the solid plastic.

10. A shot shell according to claim 9, in which the cellular expanded plastic cushion wad is surface lubricated.

15. A shot shell containing a charge of a propellant powder and a shot charge separated from said powder charge by a wad column comprising a cushion wad of permanently crushable cellular cellulose acetate plastic and a gas sealing wad.

20. A shot shell according to claim 11, in which the gas sealing wad is a felted fibrous material impregnated with a high-melting-point lubricant.
